UNITED STATES PATENT OFFICE.

HENRY G. DAWSON AND WILLIAM R. DAWSON, OF CHICAGO, ILLINOIS.

DESIGN FOR A FIREPLACE.

SPECIFICATION forming part of Design No. 23,910, dated December 25, 1894.

Application filed November 26, 1894. Serial No. 530,072. Term of patent 7 years.

To all whom it may concern:

Be it known that we, HENRY G. DAWSON and WILLIAM R. DAWSON, citizens of the United States, residing at Chicago, in the county of Cook and State of Illinois, have invented and produced a new and useful Design for Fireplaces, of which the following is a specification, reference being had to the accompanying photograph, showing the complete design.

- 5 . The principal features of our design are a pair of columns, forming the pilasters of the sides of the frame and having fluted shafts and composite capitals, irregular scroll work embellishing the transverse or top bar of the frame; a plain or polished hood; knotted fringe embellishment of the shield; and serpentine fretwork in the base of the fire place. The figures used in ornamentation are all in relief.
- 10 . The pilasters A, A, are in the form of columns having fluted shafts. The bases of the columns are encircled by doubled bands of scroll work α , α , suggestive of foliage. The pedestals of the columns are each ornamented with two nude human figures and below these figures the pedestals are crossed by a series of bands. The upper ends of the shafts are inclosed by belts having depending leaves and being expanded above to receive the capitals which are embellished with Egyptian figures. The field of the uprights of the frame is ornamented with scroll work of irregular configuration. The scroll work across the upper bar B, of the frame forms a frieze and
- 15 . is suggestive of foliage radiating from the center of the fire place.

The hood C, overhanging the fire place opening is curved, being longitudinally concave near its edges and convex across its central portion. The returns at its ends are in panels, longitudinally straight. The surface of the hood is smooth. An inner hood c, immediately below the hood C, is ornamented with pendent fern leaves, and the shield D, across the upper portion of the opening of the fire place presents the appearance of knotted fringe.

The fender E, is embellished with a garland swung from the two upper corners and having its ends pendent.

The fret work of the base F, is formed of two serpentine scrolls, generally horizontal in direction. This fret work is bordered by tracery simulating rush leaves radiating from the center of the fire place.

We claim as our invention—

The design for a fire place, substantially as herein shown and described.

In witness whereof we have hereunto affixed our signatures in the presence of two witnesses.

HENRY G. DAWSON.
WILLIAM R. DAWSON.
